Specification of Letters Patent.

Patented Sept. 1, 1914.

Application filed October 2, 1913. Serial No. 793,044.

REISSUED.

To all whom it may concern:

Be it known that I, EDWIN T. BASKIN, a citizen of the United States, residing at Independence, in the county of Jackson and 5 State of Missouri, have invented a new and useful Glove, of which the following is a specification.

The present invention appertains to 10 gloves, and aims to provide a glove of novel or unique construction, the present invention being particularly an improvement over the gloves and mittens disclosed in former Patent 15 No. 1,072,560, issued September 9, 1913, and in my co-pending applications, Serial No. 677,941 and 716,085, filed February 16, 1912, and August 20, 1912, respectively.

It is the object of the present invention to provide a glove of novel construction, as over 20 prevailing gloves, whereby the improved glove will have a minimum amount of stitching, and in order that the seams will be less exposed to wear than heretofore.

A specific object of the present invention is to provide a body blank of the nature indicated, in connection with a thumb pocket 25 formed of a blank, and stitched to the body in connection with a lining or facing for the index finger, in a peculiar manner, the body blank having a thumb lap or facing 30 which is stitched to the interior of the thumb pocket blank whereby the quirk will be of peculiar reinforced construction.

With the foregoing and other objects in view which will be apparent as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

The invention has been illustrated in its 45 preferred embodiment in the accompanying drawings wherein—

Figure 1 is a plan view of the body blank of the glove. Fig. 2 is a plan view of the thumb pocket blank. Fig. 3 is a plan view of one of the independent finger pocket 50 sections. Fig. 4 is a plan view of the lining or facing blank for the index finger. Fig. 5 is a similar view to Fig. 1 illustrating the index finger lining or facing and thumb pocket blank stitched to the body blank. 55 Fig. 6 is a view taken from the opposite

side of the body blank, as seen in Figs. 1 and 5, the thumb pocket blank being folded downward, and the thumb lap or facing of the body blank being sewed to the thumb pocket blank. Fig. 7 is a view illustrating 60 the manner of sewing the independent finger pocket sections to the body blank between the index and third finger sections. Fig. 8 is an elevation of the completed glove. Fig. 9 is a section detail taken through the 65 quirk.

The blanks from which the present glove are constructed are preferably cut from Jersey cloth, cotton, flannel or other suitable material.

The present glove embodies a main or body blank 1, comprising the symmetrical side or palm sections 2, said sections 2 being symmetrical at the opposite sides of the median line 3 of the blank 1. The side or palm 70 sections 2 are provided with integral index, third and fourth finger pocket sections 4, 5 and 6, respectively, the finger pocket sections 4 being attached at the median line of the blank, and the respective finger sections 4, 5 and 6 being separated by slits or 75 cuts extending to the palm sections proper.

The adjacent slits between the finger sections 4 and 5 extend beyond the butt or basal portions of the finger sections, as at 7, or extend 80 into the palm sections proper, the said finger sections being provided with the V-shaped notches 8 at their butt portions adjoining the slits between the said finger sections. The said notches 8 serve to distinguish 85 the main portions of the slits between the finger sections 4 and 5, and the extended portions of the slits, the extended portions of the slits being employed for the attachment of the second finger pocket sections as 90 95 will hereinafter appear.

The blank 1 is provided at its lower end adjoining its wrist portion with an ovate-acuminate slit or cut 9, which forms a thumb opening or seat and a thumb lap 10 100 of ovate acuminate contour. The blank is also provided with a short slit or cut 11 extending from the intermediate portion of the slit 9, or from the tip of the thumb lap 10 to the respective end of the blank 1, to 105 divide or separate the lower ends of the wrist portions of the side or palm sections of the blank.

The thumb pocket blank embodies the two sections 13, which are approximately of 110

ovate-acuminate contour which are integral and disposed at an obtuse angle with respect to one another.

The second or independent finger pocket 5 is constructed of two sections 14, in a manner which will be described hereinafter. The lining or facing for the index finger pocket comprises a blank 15, which is provided at its lower end with a crotch 16.

10 The side edges of the blank 1, or the remote edges of the palm sections 2 and finger pocket sections 6, are curved outwardly, as at 6^a, for the purpose which will hereinafter appear.

15 In assembling the parts of the glove, the side edges of the lining blank 15 are sewed to the inner sides of the palm sections 2 and the index finger sections 4, by the lines of stitches 17, the inner edges of the crotch 16 being disposed flush with the edges of the thumb opening of the blank 1. The edges 13' of the sections 13 of the thumb pocket blank are then stitched to the edges of the thumb opening, together with the inner edges of the crotch 16 of the index finger lining or facing 15, by a line of stitches 18, the blanks 12 and 15 being disposed upon opposite sides of the blank 1. The thumb lap or facing 10 projects from between the blanks 15 and 12, when the said blanks are secured or stitched to the blank 1, and the thumb lap or facing 10 and the blank 12 are then brought together, so that the edges of the thumb lap or facing 10 may be sewed 30 to the inner sides of the sections 13 by a line of stitches 19.

To attach the finger sections 14, the finger sections 4 and 5 of the blank 1 are spread or swung apart as illustrated in Fig. 7, where- 40 by the inner ends of the slits between the finger sections 4 and 5 will be opened. The finger sections 14 are then laid upon the proper side of the blank 1 with their butt ends disposed along the edges formed by the 45 extended portions of the said slits, the said edges then being stitched to the butt ends of the sections 14 by the lines of stitches 20. When the finger sections 4 and 5 of the blank 1 are spread or swung apart, the inner ends 50 or extended portions of the slits between the said sections will be opened, whereby the edges defined by the said portions of the slits will approximately aline, so that when the independent finger sections 14 are stitched 55 to the said edges defined by the extended portions of the slits, and when the finger sections 14 are stitched together, the finger sections 4 and 5 will be crowded apart and will be disposed angularly with respect to 60 one another as seen in Fig. 8, instead of parallel. Then, the fingers of the hand will be readily accommodated by the finger pockets, it being observed that the material from 65 which the glove or mitten is formed, is sufficiently elastic or flexible to permit the finger

sections 14 to be applied, as stated. The finger sections 14 thus being interposed between the finger sections 4 and 5 of the blank 1 are swung outwardly and the glove or mitten is completed by stitching the respective edges of the palm section thumb and finger sections together, as is well understood in the art. The curved portions or flaps 6^a may be stitched together along various lines in order to adjust the width of 70 the glove. Thus, after the portions 6^a have been stitched together, the user, if he so desires, may rip the portions 6^a apart, in order that they may be re-stitched in such a manner as to properly fit the wearer's hand. 80 The glove being thus completed will carry out the objects aimed at in a highly efficient and desirable manner, it being observed that the second finger being interposed in the manner described will cause the finger pock- 85 ets to be spread sufficiently apart to comfortably accommodate the fingers. In this manner, the usual flat condition of the glove or mitten is avoided, this flat condition of the glove or mitten being usually present 90 in reversible gloves or mittens. Attention is also directed to the fact that the lining or facing of the index finger pocket and the thumb lap or facing, in forming the lining or facing of the thumb, will protect those 95 portions of the glove, which are subject to the greatest amount of wear when the glove is employed for handling various articles.

Referring to Fig. 9, it will be noted that the blanks 1, 12 and 15 and the thumb-lap 100 or facing 10 of the blank 1 being stitched together in the peculiar manner described will provide a quirk seam of four-ply thickness, it being noted that the edge of the blank 12 which is stitched to the blank 1 is 105 turned under, while the edge of the crotch 16 is turned under the thumb pocket blank 12, together with the thumb lap or facing 10 so as to provide a protected and reinforced seam.

110 It is to be noted that the edges of the finger pocket sections being stitched together, will locate the seams between the finger pockets, in order that the seams will be protected from wear, or will be as little 115 exposed as is possible. It is also evident, that as illustrated in Fig. 7, the independent finger pocket sections 14 may be stitched to the body blank in a convenient manner, by separating the finger pocket sections 4 and 5, 120 the stitch lines 20 being practically straight, due to the opening up of the inner portions of the slits between the sections 4 and 5.

The glove may be provided with an elastic gauntlet band or wrist 21, although the 125 wrist is well known in the art and may be eliminated if desired.

In the construction of the glove, it must be observed that after several blanks have been sewed together, the blank 1 is then 130

doubled or folded upon the median line 3 to bring the side or palm sections 4 and the finger sections into coincidence. The said glove being of the reversible type, may be 5 worn on either the right or left hand.

Having thus described the invention, what is claimed as new is:—

A glove or mitten comprising a body having a thumb opening and a thumb lap, an 10 index finger lining stitched to the body and having its lower end disposed flush with the edges of the thumb opening, and a thumb pocket blank having certain of its edges disposed flush with the thumb opening, said 15 edges of the thumb pocket blank and the

lower end of the said lining being stitched to the body with the thumb lap projecting from between the said lining and the thumb pocket blank, and the thumb lap having its edges stitched to the thumb pocket blank, 20 the said edges of the thumb pocket blank being turned under adjacent the quirk.

In testimony that I claim the foregoing as my own, I have hereto affixed my signature in the presence of two witnesses.

EDWIN T. BASKIN.
